Primary Examiner — Elizabeth J Oswecki(74) *Attorney, Agent, or Firm* — Fish & Richardson P.C.(57) **CLAIM**

The ornamental design for a resonator coil, as shown and described.

DESCRIPTION

FIG. 1 is a perspective view of a resonator coil showing my new design.

FIG. 2 is a top plan view of the resonator coil of FIG. 1.

FIG. 3 is a bottom plan view of the resonator coil of FIG. 1.

FIG. 4

is a front elevation view of the resonator coil of FIG. 1.

FIG. 5

is a back elevation view of the resonator coil of FIG. 1.

FIG. 6 is a right side elevation view of the resonator coil of FIG. 1; and,

FIG. 7 is a left side elevation view of the resonator coil of FIG. 1.

The broken lines shown in the drawings represent unclaimed portions of the resonator coil and form no part of the claimed design.
